UNITED STATES PATENT OFFICE.

ROLLA M. CHASE, OF BETHEL, VERMONT.

FIRE-ESCAPE.

SPECIFICATION forming part of Letters Patent No. 277,992, dated May 22, 1883.

Application filed February 17, 1883. (No model.)

To all whom it may concern:

Be it known that I, ROLLA M. CHASE, a citizen of the United States, residing at Bethel, in the county of Windsor and State of Vermont, have invented a new and useful Fire-Escape, of which the following is a specification; reference being had to the accompanying drawings.

This invention relates to devices by which an escape can be effected from a building in case of fire or other emergency, and has for its object to provide a simple, inexpensive, and efficient device that can be conveniently transported and readily placed in position for operation.

In the drawings, Figure 1 is a perspective view of my improved escape apparatus in position for use. Fig. 2 is a vertical detail sectional view of the same. Fig. 3 is a top detail view of the sliding cylinder. Fig. 4 is a cross-section on the line *xx*, Fig. 2.

Referring to the drawings, A designates a flexible cable or rope, that is arranged to be secured to a hook, B, or other device inside a window, and to be dropped out of the window, so as to hang from the same and extend nearly to the ground, as shown in Fig. 1 of the drawings.

At the bottom of the cable A is secured a coiled spring, C, that encircles the same for some distance from its lower end, and is provided on top with a plate, D, against which the sliding escape device may strike to break the force of the descent in case the latter is made too rapidly.

E designates the tubular device that is arranged to slide on the said rope or cable. This device is preferably constructed, in the main, of metal, and comprises a tube or cylinder, F, having a central longitudinal bore or perforation, G, through which the cable A passes, and provided with lateral flanges H I, respectively extending around its top and bottom. These flanges serve to obviate liability of the person's hands, which grasp the tubular portion of the device, running off onto the cable during the descent. At its top end the cylinder F is provided with a slot or opening, J, from which project lugs or flanges K K, between which is fulcrumed on a cross-pin, L, a friction-lever, M, having its end N working

through the slot J into the longitudinal perforation G, and formed with a concavely-grooved edge, O, that clamps the cable A. To the other end of the lever M is secured a strap, P, that passes through a slot, Q, in the flange I, and is provided at its free end with a hook, R, or other device, by which it can be attached to a loop or staple, S, on the under face of the said flange I.

T is an adjustable collar that is provided with a set-screw, U, and is arranged on the strap P between its secured end and where it passes through the slot Q.

The operation and advantages of my invention are obvious. When it becomes desirable to use the apparatus it is only necessary to secure the end of the cable to the hook inside the window and throw the end of the rope or cable having the spring out of the same. Then pass the strap P around the body under the arms, and secure its end to the staple, after which the tubular portion of the device and the friction-lever are grasped with the hands, and the person throws his weight on the strap P and leaves the window. As soon as the weight of the person comes on the device E the strap P is drawn through the slot Q until its passage is arrested by the collar T, which has been previously adjusted as desired. This movement of the strap will operate upon the friction-lever to force its end N against the cable, and the friction caused by the end N so clamping the cable will enable the device E to descend slowly to the ground. If the descent is being too rapid, or it is desired to stop, it is only necessary to further depress the lever M with the hands, which will more firmly clamp the end N against the cable and increase the friction sufficiently to retard or stop the descent at any desired point. The speed of the descent can thus be regulated as desired.

I claim as my invention—

1. The combination of a tubular or cylindrical stem, a friction-lever fulcrumed thereon, a strap secured to the end of the lever and passing through a slot in the stem, and a collar or stop adjustable on said strap between its secured end and where it passes through the slot, as set forth.

2. The combination, with a tubular stem

having the lateral flanges at its top and bottom, in the bottom one of which is formed a slot, and with a friction-lever fulcrumed on the stem, of a supporting-strap secured to the end of the lever, passing down through the said slot, and brought up and secured to the under side of the bottom flange, as set forth.

In testimony that I claim the foregoing as my own I have hereto affixed my signature in presence of two witnesses.

ROLLA M. CHASE.
